CAN OPENER

Clayton M. Boudette, Revere, Mass.

Application May 19, 1932, Serial No. 612,252

7 Claims. (Cl. 30—3)

This invention relates to can openers and especially to improvements in the step-by-step cutting type of can opener enabling the circular incision to be made rapidly and at a location such 5 that the line of separation permits a lifting of the severed cover from the can without handling, that is, while still gripped by the can opener.

The nature of the invention and the features of construction whereby the objects sought are 10 attained will readily be understood from the following detailed description in connection with the accompanying drawing, the invention being set forth in its true scope in the appended claims.

In the drawing illustrating the preferred form 15 of the invention,

Figure 1 is a view, in perspective, of the can opener applied to the rim of a can to be opened;

Fig. 2 is a view, in plan, of the under side thereof with the handles closed and the cutter turned 20 to an operative position;

Fig. 3 is a view, in elevation, of the inner edge of the cutting arm with the cutter swiveled to cutting position;

Fig. 4 is a view, in elevation, of the inner edge 25 of the gripping arm with the gripper closed; and

Fig. 5 is a detail, in perspective, showing the gripper of the gripping arm open.

In the embodiment of the invention illustrated 30 in the drawing the can opener comprises only four articulated parts namely a rigid cutting arm 10 having a suitable cutter 12 mounted thereon and an articulated gripping arm 14 having opposed can-rim gripping abutments on a head 35 portion 16 and a handle portion 18 that are pivoted to permit gripping and ungripping. The rigid cutting arm 10 comprises a handle portion 20 and an off-set head portion 22. The two off-set head portions are each inwardly inclined 40 relatively to their handle portions permitting these heads to overlap and be pivoted at 24 when the handles are closed (see Fig. 2). It will be observed that all parts of the can 45 opener can readily be stamped to the required shapes thus reducing the expense of manufacture to a minimum.

Considering that Fig. 1 shows the front and Fig. 2 the under faces of the can-opener, gripping arm head 16 comprises a rear off-set from 50 a short and narrowed connecting portion 26 which overlies the outer margin of one end of the handle 18 and is pivoted thereto, off-center, at 28. Obviously 26 forms a front off-set with respect to the head 16. At the under face of this 55 head 16 is a narrow gripping abutment 30 op-

posed to a similar gripping abutment 32 on the handle 18 the metal of the off-set connection and the handle end both flaring outwardly (Fig. 2) to provide for effectively gripping can rims of different diameters. A stop 34 pressed through 60 the handle from rear to front limits the extent of opening of the gripper (see Fig. 5).

The cutting arm head 22 comprises a rigid front off-set on the handle 20 having a narrowed portion 36 formed by its inner margin being 65 sheared and pressed rearward into the plane of the handle 20 to form a seating abutment 38 spaced from a similar marginal seating abutment 40 on the handle. The off-set connection flares outwardly (see Fig. 2) as on the gripping 70 arm.

The rigid cutting arm has the strap-like blade 12 swiveled at its under face on a rivet 13 (Figs. 2 and 3) the inner end 42 being a knife edge. It will be observed (see Fig. 3) that the seating abutment 38 preferably is pressed into a plane slightly above the plane of the upper face of the cutting edge 42, allowing a clearance when the cutter is swiveled inward to oblique cutting position against a stop 44 that is pressed from 75 rear to front through the handle 20. This allows for the thickness of the can head and enables a grip thereon.

In applying the can opener (see Fig. 1) first 80 the two arms are opened which at the same time opens the gripping abutments 30 and 32. Struck up spurs 46 and 48 on the heads 16 and 22 respectively, serve to limit the extent of opening. The 85 opener is laid on the can head with its rim running between the two pairs of seating and gripping abutments, the bridging off-sets 26 and 36 serving to hold these at the rim. The blade 12 is then turned until the corner of the 90 knife edge 42 engages the can wall just below the rim, or the knife edge may be forced through the 95 wall of the can if desired. Ordinarily the closing movement of the handles, the next movement, will automatically enter the knife in the can due to its oblique position. By holding the cutting arm 10 stationary and closing the gripping 95 arm 14 upon it, the handle 18 will first pivot on its head 16 gripping the rim between the abutments 30 and 32 and the can will then be rotated 100 past the fixed cutter 12 making a slit in the can wall. The grip on the rim is released by moving 105 handle 18 away from handle 20 and the gripping arm then slides along the can rim to position for a second closing and cutting movement, and so on until the can top is completely severed. At 110 the end of the cutting operation the can top stays

in the can opener by reason of the inward position of the cutter 12 underlying the seating abutment 38. Thus the severed can top may be lifted from the can body without handling, but its rim 5 will drop out of position between the two seating abutments 38 and 40 immediately the cutter is turned back into inoperative position.

Obviously the mode of operation described may be reversed, the gripping arm being held stationary during a cutting operation and then released and moved away from the cutting arm, that has been closed upon it, for each succeeding cutting operation. In this case the cutter moves relatively to the stationary can. The can opener is 15 particularly effective in opening hot cans because in any mode of operation no handling of the can is required, even to remove the severed top. The line of severance is even and clean and all difficulty from jamming by the knife walking away 20 from the rim is eliminated.

The nature and scope of the invention having been indicated and its preferred embodiment having been specifically described, what is claimed as new, is:—

25 1. A can opener having a rigid arm and an articulated arm pivoted together at one end, each of said arms being provided with a pair of opposed abutments at its under face adapted to receive the can rim between them, and said rigid arm having a cutter at its under face provided with a knife edge adapted to sever the can wall below the can rim.

30 2. A can opener according to claim 1 in which said cutter consists of a blade pivotally mounted on said rigid arm and having its knife edge at one end.

35 3. A can opener according to claim 1 in which said cutter consists of a pivotally mounted blade

having a knife edge at its inner end adapted to lie below the opposed abutments on said rigid arm when turned into cutting position.

4. In a can opener of the type described a cutting arm having a handle, a head off-set upwardly from said handle having two opposed, spaced abutments at the junction of the handle and the head and lying substantially in the plane of the handle, said off-set head being narrower than the handle in the region of said abutments.

80 5. A cutting arm for can openers as described by claim 6 having a cutting blade pivoted to lie flat against the under face of the handle and movable about its pivot to cutting position, and a stop at the inner edge of said blade to limit its angular movement relatively to the handle.

85 6. A stamped metal can opener having one rigid arm provided with a front off-set head, one articulated arm provided with a rear off-set head, said heads being pivoted together, integral abutments on each arm to lie inside and outside the can rim, and a cutting blade lying flat relatively to and carried beneath said rigid arm.

90 7. A can opener comprising two arms pivoted together at one end, each of said arms having a 100 pair of opposed, spaced abutments at its rear face one of each pair to seat inside and the other outside of the can rim, an off-set portion at the front face of each arm bridging the abutments thereof, one arm being rigid and carrying a cutter independent of and lying beneath the abutments on that arm, and the other arm being articulated and having a handle portion pivoted off-center at the inner end to its bridging off-set, said inner handle end forming one of the opposed abutments 105 on said articulated arm.

CERTIFICATE OF CORRECTION.

Patent No. 1,960,525.

May 29, 1934.

CLAYTON M. BOUDETTE.

It is hereby certified that error appears in the printed specification of the above numbered patent requiring correction as follows: Page 2, line 87, claim 5, for the claim numeral "6" read 4; and that the said Letters Patent should be read with this correction therein that the same may conform to the record of the case in the Patent Office.

Signed and sealed this 24th day of July, A. D. 1934.

Bryan M. Battey

(Seal)

Acting Commissioner of Patents.
